DISPLAY RACK

Lee L. Levering, Tulsa, Okla.

Application October 21, 1936, Serial No. 106,788

1 Claim. (Cl. 35—56)

This invention relates to an apparatus for displaying fabric samples and more particularly for displaying clothing materials which are to be made up into wearing apparel.

It is customary for tailor and like shops to provide show rooms for the presentation to prospective purchasers of different types of materials to be made into clothing. The samples of materials are shown in varying sizes, but regardless of the size of the samples shown, it is difficult for the purchaser to picture the garment as it will appear when in finished condition.

It is, therefore, the principal object of the present invention to provide a device to aid a purchaser in visualizing the characteristics of a completed garment when viewing only a sample of material from which the garment is to be made.

Other important objects of the invention are to provide a display rack in conjunction with the visualizing apparatus having arms to which various samples of material may be attached, the arms being movable in the nature of the leaves of a book, whereby a great number of samples may be displayed; and to provide the visualizer with means rendering it engageable over any of the arms carrying a particular sample of material to furnish a display of both front and back views of a garment as it will appear when completed.

In accomplishing these and other objects of the present invention, I have provided improved details of structure, the preferred form of which is illustrated in the accompanying drawings, wherein:

Fig. 1 is a perspective view of a display rack provided with visualizers embodying the features of the present invention.

Fig. 2 is a perspective view of the display rack showing the back view of the man's figure illustrated in Fig. 1.

Fig. 3 is a plan view of the display rack showing the assembly of the pivoted arms on a rack and their susceptibility to movement in the nature of the leaves of a book.

Fig. 4 is a vertical cross-section on the line 4—4, Fig. 3, particularly illustrating the pivot points of one of the arms on the rack and the diagonal brace for the arm.

Fig. 5 is a detail perspective view of an upper corner of the rack, part of the angle members being broken away to show the pivot points for the arms and the connection of the angle members to the side rails of the base.

Fig. 6 is a fragmentary perspective view of an arm member to which samples of clothing ma-

terial are attached and over which a pair of connected visualizers are hung to display the material in the form of garment desired.

Fig. 7 is a perspective view of the hinged panels or visualizers which are hung over the arms carrying the materials to display the completed form of garment.

Referring more in detail to the drawings:

1 designates an apparatus for displaying fabric samples generally comprising an upright pedestal, 10 standard, support or base 2, substantially horizontally disposed arm members 3 pivotally mounted on the base, and a pair of hinged panels or visualizers 4 engageable over the respective arms and having transparent portions to display clothing materials 5 secured to the arms in such a manner as to resemble a garment made up from the particular material displayed.

The standard 2 includes feet 6 of any suitable material of a size large enough to rigidly support 20 upwardly extending side members 7. Rails 8 are provided coextensively with the rear edges of the side members on the inside faces thereof, the rails having their upper ends terminating short of the upper ends of the side members and suitably secured thereto throughout the length thereof. Seated on the upper ends of the rails 8 is a bracing cross member 9 of any suitable design to enhance both the rigidity and appearance of the base. A bracing cross member 10 may also 30 be interposed between the side members adjacent the feet of the base for additionally supporting same.

Suitably fixed to the rails 8 in vertically spaced relation to each other and at points substantially 35 above the mid-portion of the rails are brackets 11 to which are welded or otherwise suitably secured at the upper edges thereof upper and lower rack bars 12 and 13 which extend laterally between the rails 8 in parallel relation to each 40 other.

The rack bars preferably comprise angle irons having front flanges 14 which extend downwardly to form aprons and top flanges 15 extending horizontally relative to the base which 45 are provided with holes 16 spaced laterally from each other in accurate vertical alignment.

Mounted in the holes 16 of the upper horizontal rack bar and ordinarily hidden from view by the apron are pivot pins 17 of arm supporting 50 plates 18, the plates being formed by flattening the greater portion of the pins 17 and bending them at substantially right angles thereto. The plates 18 support the inner ends of cloth supporting arms 19, which are preferably formed 55

of wood and are of a size suitable for displaying a "pants length" of material, in pivotal condition relative to the rack bar. The outer ends 20 of the arms are provided with bracing rods 21 on the under faces thereof which are secured to the arms by plates 22 formed by flattening the rods at their upper ends and extending fastening devices therethrough and into the arms 19. The rods 21 are then bent downwardly to extend 10 diagonally in the same vertical planes as the pairs of vertically aligned holes 16 in the rack bars and are then bent further downwardly at their ends to provide pivot pins 23 engageable in holes in the lower rack directly below the pivot points 15 at the inner ends of the arms.

It is thus apparent that a swinging movement is provided for the arms so that they may be turned in the nature of the leaves of a book.

Mounted on the arms 19 are pieces or samples 20 24 of material which are secured to the arms in any suitable manner, here shown as by thumbtacks 25.

As shown in Fig. 4, the pieces of fabric hang downwardly in substantially vertical planes. It 25 is obvious that the pieces of fabric may also be folded over the arms, in which case the ends of the fabric also hang downwardly over the arms in substantially vertical planes, which ends may be easily arranged to hang in equal lengths.

With the construction thus far described materials may be effectively displayed. When, however, the materials are to be used for clothing such as men's and women's suits, dresses and overcoats, it is difficult for a prospective purchaser to visualize the garment as it will appear when made up into a finished article of wearing apparel.

I, therefore, provide panels 26 of any suitable material, for example Celluloid or some similar 40 regenerated cellulose composition of a size to substantially cover the respective samples on display on the pivoted arms. The upper ends of the panels are secured together to provide a hinge-like structure, as shown at 27, so that a 45 pair of the connected panels may be suspended over an individual arm carrying samples of material, to show the samples on both sides of the arm. I preferably secure the ends of the panels together by a strip of leather, or the like, but 50 it is to be understood that a pair of clips, or some similar device, may be used to attach the panels in such a manner that they may be suspended over any of the arms. The hinged panels are respectively provided, preferably on the inside faces thereof, with outlines for representations of front and rear views of the figure of a man or a woman wearing any suitable model suit, dress or coat. The figures are outlined by an opaque substance, such as paint or the like, as at 28, in such a manner that the effect is that 55 of an opaque panel with transparent portions showing the figures on the panels.

The details of construction of the particular garment, for example, its lapels 29, pocket flaps

30, buttons 31, cuffs 32, belt 33, collar 34 and the like, may be painted on the panel in their proper 5 positions with suitable colors and fixity in order to permit ready alteration thereof incidental to changes in current fashions and seasons. The 10 face 35, hands 36, neck 37, accessories and shoes 38 of the figures may be painted in their proper 15 places for permanent fixation in proper opaque colors in order to enhance the appearance of the figure outlined on the panel and to portray a fully dressed person wearing a garment suitable to the prospective purchaser in the pattern and grade of material of the customer's choice.

It is thus apparent that the customer may easily visualize the appearance of the finished 15 garment he is about to order by merely viewing the outlined fabric through the transparent portions of the panels, when the panels are placed over the pieces of fabric, so that he may avoid mistakes in selection and later dissatisfaction with 20 the completed garment. The saleswork of the person making the sale will also be materially lessened for the reason that fewer details concerning the garment will have to be explained to the purchaser.

In operating a device constructed as described, 25 having in mind that a prospective purchaser is viewing a particular sample of material suspended from one of the pivoted arms, the hinged panel 4 is hung astraddle the arm and the front 30 and rear outlines of a chosen figure overlie the material to reveal or depict a human figure clothed in a garment of that particular material as it will appear when completed.

The same sample of material may be on both 35 sides of the pivoted arm, in which case that arm may be moved back and forth in the nature of one of the leaves of a book to display the front and back portions of the garment illustrated on the panels, thus permitting the customer to 40 visualize, before ordering, how the garment will look when made up.

What I claim and desire to secure by Letters Patent is:

In an apparatus of the character described, a 45 support resting on a floor and comprising a substantially horizontal member spaced from the floor, a piece of fabric folded over the horizontal member at a point substantially midway the length of the piece of fabric, a pair of panels 50 each having a transparent portion outlined by front and rear representations respectively of a garmented human figure, and flexible means hingedly connecting the upper ends of the panels together, the hinged panels being engageable 55 over the supported portion of the piece of fabric and about the outer faces of the hanging ends of the piece of fabric, the transparent portions of the panels revealing the piece of fabric when viewed through the panels in respective representation of front and rear views of a human figure clothed in a garment made from the piece 60 of fabric.

LEE L. LEVERING.
